US0D1011533S

(12) **United States Design Patent** (10) **Patent No.:** **US D1,011,533 S**
(45) **Date of Patent:** **** Jan. 16, 2024**

(54) **BLOOD GLUCOSE METER**

(71) Applicant: **SHENZHEN IMDK MEDICAL TECHNOLOGY CO., LTD**, Shenzhen (CN)

(72) Inventor: **Changchun Xia**, Wenzhou (CN)

(73) Assignee: **SHENZHEN IMDK MEDICAL TECHNOLOGY CO., LTD**, Shenzhen (CN)

(**) Term: **15 Years**

(21) Appl. No.: **29/805,110**

(22) Filed: **Aug. 25, 2021**

(51) **LOC (14) Cl.** **24-02**

(52) **U.S. Cl.**

USPC **D24/169**

(58) **Field of Classification Search**

(57) **CLAIM**

The ornamental design for a blood glucose meter, as shown and described.

DESCRIPTION

FIG. 1 is a front, right side, bottom perspective view of a blood glucose meter, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The dashed broken lines in the drawing depict portions of the blood glucose meter that form no part of the claimed design.

1 Claim, 7 Drawing Sheets
